MAKE-AND-BREAK DEVICE FOR PERIODIC OR CYCLIC APPLICATION OF FLUID PRESSURE

Howard L. McCombs, Jr., South Bend, Ind., assignor to Bendix Aviation Corporation, South Bend, Ind., a corporation of Delaware

Application May 10, 1952, Serial No. 287,200

8 Claims. (Cl. 137—103)

The instant invention had its inception in the need for a simple and convenient yet effective means for working or "exercising" the air and fuel diaphragms and associated parts used for controlling the regulator valve of Stromberg injection carburetors. When such a carburetor is overhauled after a given number of hours of flight service and re-assembled and reset it is customary to work or exercise the moving parts to ensure against sluggish action and sticking or in other words, to stabilize the carburetor and minimize any tendency toward subsequent "drift," viz., departure from the final calibration and adjustment to specifications. Thus, the diaphragms may lose some of their flexibility during overhaul and there may be burrs or rough spots on replaced parts. Hence the carburetor is "run in" before it is again put in flight service. Such working may also be advisable or necessary in any carburetor whether after assembly and adjustment at the factory or following a certain period of non-use at the factory or in the field. However, the device of the present invention has been found to be exceptionally convenient for use in the field where the more elaborate equipment and experienced personnel usually found at the factory is not available. Obviously, such a device is not restricted in service to exercising or working carburetors but may be used wherever the application of periodic or cycle pulsations of fluid pressure may be necessary or desirable.

An object of the invention, therefore, is to provide a device for producing periodic or intermittent fluid pressure pulsations at any desired point of application.

Another object is to provide a device of the type specified which is simple and compact in construction and capable of being used by unskilled personnel.

Another object is to provide a device for producing fluid pressure pulsations wherein the amplitude and frequency of the pulsations may be varied as desired simply by substituting different relative sizes of restrictions or bleeds.

The foregoing and other objects and advantages will become apparent in view of the following description taken in conjunction with the drawing, wherein the sole figure illustrates in sectional schematic a device in accordance with the invention.

Referring to the drawing, a casing or hollow housing is generally indicated at 10; it is made up of a main body section 11 and an upper section or cap 12, having a flange 13, which is secured to the base 11 by means of screws 14. A diaphragm 15 has its peripheral edge clampingly engaged between the flange 13 and adjacent wall of the base 11, said diaphragm forming a movable wall between atmospheric chamber 16 and suction chamber 17. A valve 18, shown in a form of a flat disc of suitable material, is secured to the central portion of the diaphragm 15 by means of a screw bolt 19 and bushings 20 and 21. The valve 18 serves as an intermittent closure for suction chamber 22. The chamber 16 is vented to the atmosphere at 23.

A suitable source of suction or vacuum, not shown, is connected by means of air line 24 and restriction or bleed 25 to the chamber 22; and leading from said chamber

2

through restriction or bleed 26 is another air line 27, which is adapted for connection to the point of intermittent or periodic application of suction, here chamber B of a carburetor regulator section. An air line 27' communicates the said chamber B with suction chamber 17 through a restriction or bleed 28.

As heretofore noted, the illustrated embodiment of the invention is shown as applying periodic pulsations to the regulator section 30 of a Stromberg carburetor. That portion of the regulator shown comprises a regulator valve, the stem of which is indicated at 31, which is connected by means of a series of coating bushings 32 to the central portion of a series of diaphragms 33, 34 and 35. The diaphragm 33 is commonly known as the air diaphragm, and it forms a movable wall between impact pressure chamber A and venturi suction chamber B; whereas the diaphragm 34 is commonly known as the fuel diaphragm and forms a movable wall between metered fuel chamber C and unmetered fuel chamber D. When the carburetor is functioning on an engine, an air differential pressure is set up across the diaphragm 33, which varies as a function of the velocity of the air flowing to the engine, and a fuel differential pressure is set up across the diaphragm 34, which varies as a function of the rate of flow of fuel to the engine. These respective differentials oppose one another and act through the diaphragms to so position the regular valve as to maintain a given fuel head across the carburetor metering restrictions, not shown, for a given rate of mass air flow.

30

Operation

The effective or exposed area of the valve 18 is less than that of the diaphragm 15. For example, valve 18 may have an effective area of say one-third of that of diaphragm 15. When suction or P1 pressure is applied through the air line 24, the P2 pressure in chamber 22 drops, and this low pressure or suction is communicated through bleed 26 and air line 27 to the regulator chamber B and thence by way of air line 27' and restriction or bleed 28 to chamber 17. The pressures in air lines 27 and 27' and chamber 17 are indicated, respectively, as P3, P4 and P5 pressures. The low pressure P2 or suction force in chamber 22 tends to hold valve 18 to its seat. However, since the diaphragm 15 is of greater effective area than that of the valve 18, when the suction in chamber 17 has increased to a certain point, the force P5 applied to the diaphragm 15 becomes sufficient to overcome the resisting force or suction P2 holding the valve to its seat, whereupon the valve snaps open and atmospheric pressure in chamber 16 is communicated to chamber 22 and in turn builds up in conduit 27, regulator chamber B, conduit 27' and chamber 17; and as it builds up in the latter chamber, the gravity effect or weight of the valve assembly causes the valve again to seat and the cycle is repeated. Optionally, a spring 36 may be provided to ensure seating of the valve, particularly where a vertical position is not convenient.

By varying the relative sizes of the restrictions or bleeds 25, 26 and 28 the frequency and amplitude of the pulsations may be varied within limits at a given value of applied suction. For example, a decrease in the size of restriction 26 at a given size of restriction 28 will result in a cycle of less frequency and amplitude, since it will require a longer period of time for the suction force P5 to build up in chamber 17 and hence there will be a longer dwell of valve 18. By decreasing the size of restriction 28 at a given size of restriction 26, the amplitude of each cycle is increased and the frequency decreased. A change in size of restriction 25 has only a minor effect on cycle amplitude and frequency.

The frequency or cyclic rate can also be varied by varying the relative areas of diaphragm 15 and valve 18, if

being understood of course that the effective area of the valve should always be less than that of the diaphragm.

Although only one embodiment of the invention has been shown and described, certain changes in form and relative arrangement of parts other than those above specified may be made to suit requirements.

I claim:

1. A device adapted to be interposed in a fluid pressure or suction conduit between a source of pressure and a point of applied pressure for producing fluid pressure pulsations at said point, comprising a housing, a flexible wall in said housing dividing the interior thereof into first and second chambers, a passageway connecting said first chamber with said conduit, a port in said housing formed to connect said first chamber with a source of higher pressure, means for connecting said second chamber with said conduit posterior said first chamber, a valve in said housing adapted to control the communication between said port and said passageway, the effective area of said valve exposed to conduit pressure being less than that of said flexible wall, and means operatively connecting said wall and said valve.

2. A device adapted to be interposed in a low pressure or suction conduit between a source of pressure and a point of applied pressure for producing fluid pressure pulsations at said point, comprising a housing, a flexible wall in said housing dividing the interior thereof into first and second chambers, a passageway connecting said first chamber with said conduit anterior the point of applied pressure, a port in said housing for communicating said first chamber with a source of higher pressure such as the atmosphere, a valve in said housing for alternately closing said passageway and communicating the latter with said port, means for connecting said second chamber with said conduit posterior the point of applied pressure, means operatively connecting said wall and said valve, the effective area of said valve exposed to conduit fluid pressure being less than that of said flexible wall, and a restriction in said first-mentioned means between said first and second chambers.

3. A device adapted to be interposed in a low pressure or suction conduit between a source of pressure and a point of applied pressure for producing fluid pressure pulsations at said point, comprising a housing, a flexible wall in said housing dividing the interior thereof into first and second chambers, a passageway connecting said first chamber with said conduit anterior the point of applied pressure, a port in said housing for connecting said first chamber with a source of higher pressure such as the atmosphere, a valve in said housing for alternately closing said passageway and communicating the latter with said port, means for connecting said conduit with said second chamber posterior the point of applied suction, the effective area of said valve exposed to conduit fluid pressure being less than that of said wall, one or more restrictions in said means between said chambers and the point of applied pressure, the frequency in amplitude of pulsations being variable by varying the effective size of said restrictions, and means operatively connecting said wall and said valve.

4. A device adapted to be interposed in a low pressure or suction conduit between a source of pressure and a point of applied pressure for producing fluid pressure pulsations at said point, comprising a housing, a diaphragm in said housing dividing the interior thereof into first and second chambers, a port in said housing exposing said first chamber to a source of higher pressure such as the atmosphere, a passageway connecting said first chamber with said conduit, a valve in said housing effective to alternately close said passageway and to expose the latter to a source of higher pressure, resilient means urging said valve toward closed position, means operatively connecting said diaphragm and said valve, means con-

necting said second chamber with said conduit, said diaphragm being exposed on one side to the fluid pressure in said conduit posterior said first chamber and arranged to urge said valve in an opening direction, the effective area of said valve being less than that of said diaphragm, and one or more restrictions in said means between said chambers.

5. A device for use with a source of pressure for producing pressure pulsations at a point of applied pressure, comprising a housing having a hollow interior, a movable wall dividing the housing into first and second chambers, an inlet for each of said chambers, a port in said housing establishing direct communication between said first chamber and the atmosphere, a conduit adapted to connect said inlets to a source of pressure, and a valve in the first chamber operably connected to said movable wall for alternately opening and closing the inlet of said chamber.

10 6. A device adapted to be interposed in a conduit between a source of pressure and a point of applied pressure for producing fluid pressure pulsations at said point, comprising a housing having a hollow interior, a movable wall dividing said housing into two chambers, a vent in said housing establishing direct communication between one of said chambers and the atmosphere, an inlet for said vented chamber connected with said conduit anterior to the point of applied pressure, an inlet for the other chamber connected with said conduit posterior to the point of applied pressure, and a valve in said 15 vented chamber operably connected to said movable wall for alternately opening and closing the inlet of said chamber.

20 7. A device for use with a source of pressure for producing pulsations at a point of applied pressure comprising a housing, a movable wall in said housing dividing the interior thereof into first and second chambers, a conduit for connecting the first chamber with said source, a port in said housing for connecting said first chamber with the atmosphere, a valve in said housing formed to control the communication between said first 25 chamber and said conduit, said valve located and arranged to be urged by gravity in a direction to close said conduit, a passageway for connecting said source with said second chamber, the area of said valve exposed to said source of pressure being less than that of said wall, and means operatively connecting said wall and valve.

30 8. A device for use with a source of pressure for producing pulsations at a point of applied pressure comprising, a housing, a movable wall in said housing dividing the interior thereof into first and second chambers, a conduit for connecting the first chamber with said source of pressure, means in said housing for connecting said first chamber with a source of higher pressure, a valve in said housing movable to open or close said conduit, said valve adapted to be held in closed position 35 by the pressure differential between said first chamber and said conduit, a passageway for connecting said second chamber with said source of pressure, the area of said valve exposed to said source of pressure being less than that of said wall, and means operatively connecting said 40 wall and valve.
